US00D783568S

(12) **United States Design Patent** (10) Patent No.: **US D783,568 S**
(45) Date of Patent: **** Apr. 11, 2017**

(54) **MOUNTABLE PHONE**

(71) Applicant: **Cisco Technology, Inc.**, San Jose, CA (US)

(72) Inventors: **Alex Pista**, San Jose, CA (US);
Michael Lenz, Lake Oswego, OR (US);
Paolo Sandro Trevisan, Miami, FL (US); **Francisco Barboza**, Miami, FL (US)

(73) Assignee: **Cisco Technology, Inc.**, San Jose, CA (US)

(**) Term: **15 Years**

(21) Appl. No.: **29/552,280**

(22) Filed: **Jan. 21, 2016**

(51) LOC (10) Cl. **14-03**

(52) U.S. Cl.

USPC **D14/144**; D14/248

(58) **Field of Classification Search**

USPC ..... D14/140, 140.1, 140.3, 142, 144, 148, D14/188, 217, 240, 243, 247, 248, 251, D14/252, 253, 299, 329, 138 G, 138 AA; D21/517; D13/107, 108, 162; 379/21, 379/325, 328, 330, 369, 370, 426, 449, 379/450, 455, 210.02; 710/303, 304

(57) **CLAIM**

We claim the ornamental design for a mountable phone, as shown and described.

DESCRIPTION

FIG. 1 is a perspective view of a mountable phone, showing our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a partially exploded, front-right perspective view thereof; and,

FIG. 9 is a partially exploded, rear-right perspective view thereof.

The broken lines in the drawings depict parts of the mountable phone that form no part of the claimed design.

1 Claim, 9 Drawing Sheets
